(57) **CLAIM**

We claim the ornamental design for display screen with graphical user interface, as shown and described.

DESCRIPTION

FIG. 1 is a front view of a display screen with graphical user interface showing a second embodiment of my new design; and,

FIG. 2 is a front view of a display screen with graphical user interface showing a third embodiment of my new design. The broken line showing of the remainder of the display screen in FIGS. 1-2 is for environmental purposes only and forms no part of the claimed design.

1 Claim, 2 Drawing Sheets

FIG. 1

FIG. 2
